G. B. WOOD ET AL

GATE

Filed March 31, 1922

UNITED STATES PATENT OFFICE.

GEORGE B. WOOD, WILLIAM C. BIRD, AND ERNEST B. PACKARD, OF ROCKLAND,
MAINE.

GATE.

Application filed March 31, 1922. Serial No. 548,270.

To all whom it may concern:

Be it known that we, GEORGE B. WOOD, WILLIAM C. BIRD, and ERNEST B. PACKARD, citizens of the United States, residing at 5 Rockland, in the county of Knox and State of Maine, have invented certain new and useful Improvements in Gates, of which the following is a full, clear, and exact description.

10 This invention relates to gate devices for controlling the passage of a substance such as coal or limestone, for example, through an aperture or chute in a lateral retaining wall.

15 In removing by gravity coal, ore, limestone, or other substances having similar physical characteristics, from the bins, dumps, or piles in which they are stored, difficulty has been experienced in controlling 20 the movement of the substances, the movement being difficult to start and to check.

An object of this invention is to provide 25 an improved gate device for controlling such movements, which effectively controls the starting and checking of the movements; which permits of a comparatively accurate and variable regulation of the quantity of 30 the substance passing through the aperture or chute at each movement; which may be controlled and operated in a simple manner with little manual effort; which may be attached to a lateral or retaining wall and which is simple and inexpensive in construction.

35 Other objects and advantages will be apparent from the following description of an embodiment of the invention and the novel features will be particularly pointed out in 40 claims.

In the illustrated embodiment—

Figure 1 is an elevation of a lateral retaining wall for a pile of coal or limestone having discharge apertures or chutes to 45 which a gate device constructed in accordance with the invention has been applied;

Figure 2 is a sectional elevation of the same taken substantially along the line *a*—*a* in Figure 1 and looking in the direction of the arrow; and

Figure 3 is a sectional plan of the same taken substantially along the line *b*—*b* of Figure 1 and looking in the direction of the arrow.

55 In the illustrated embodiment a wall 1

may be either a retaining wall for a side of a pile of coal or limestone or it may form a lateral wall of a bin in which the limestone or coal or other material having similar physical characteristics, is stored. The wall 60 is reinforced by a plurality of spaced upright studs 2 and cross studs 3 and 4. The wall 1 is provided at spaced points therealong and between the pairs of upright studs 2, with discharge apertures 5 through which 65 the limestone, coal or similar material is to pass. A chute 6 is fitted into each of these apertures and is provided with a bottom wall 7 which slopes downwardly and away from the wall 1. A pair of sector members 8 70 are pivoted at their apex ends to the chute at points adjacent the discharge aperture with the axis of the pivots lying substantially in the plane of the bottom wall 7 of the chute. An arcuate cross plate 9 connects 75 the outer ends of the sector members 8, the curvature of the plate 9 being cylindrical with the axis of curvature lying substantially in the axis of rotation of the sector members 8. The cross plate abuts closely 80 against the outer and lower edge of the bottom wall 7 of the chute so that as the sector members are carried upwardly the cross plate will move from below the bottom wall 7 upwardly across the discharge aperture 85 of the chute to various extents. The limestone passing along the bottom wall of the chute will engage the cross plate and its movement will be checked thereby.

Pulleys 10 are disposed at each side of the 90 discharge aperture and supported from the cross stud 3. Similar pulleys 11 are carried by the lower cross stud 4. An endless flexible cable 12 passes over the pair of pulleys at each side of each chute, and each cable at 95 one point 13 is connected to the adjacent side of the sector member 8 so that movements of the cable 12 will impart a corresponding movement to the sector members and the cross plate 9. The sector members 100 and the cross plate together form a gate member which is controlled by the endless cables at each side thereof.

An air hoist 14 is suspended from the cross stud 3 between each pair of pulleys 10. 105 The movable piston 15 of the air hoist is connected at its lower end through a cable 16 to a heavy weight 17, which may be conveniently formed of concrete. The weight 17 is connected at its opposite ends 110

2

to the endless cables 12 by suitable connectors 18, so that if the weight is released it will descend and cause a movement of the cables 12 in one direction and through them cause a movement of the gate member in one direction. When the air hoist is rendered active the movable plunger 15 thereof will be elevated and the weight 17 will be elevated and held in elevated position. The elevation of the weight 17 will cause a movement of the cables 12 in a reverse direction and this reverse movement of the cables will cause a reverse movement of the gate member. A suitable controlling valve 19 is provided for each air hoist and flexible operating cords 20 extend from the arms of the controlling valve 19 so that an operator standing at one side of the chute will be able to control the activity of the air hoist and through it control the movements of the weight and gate member. The connections between the weight and the members 12 are preferably such that when the weight is released the cables will be moved in a direction to pull the gate member upwardly so as to restrict the flow of coal or limestone through the chute. The upward limit of movement of the gate member is reached when the weight 17 rests upon the upper face of the chute. By operating the air hoist the movements of the gate member may be easily controlled so that the flow through the chute may be accurately controlled and measured.

35 A plurality of heavy finger bars or irons 21 are pivotally suspended at 22 from the upper wall of the chute for movement inwardly and outwardly in the chute. These bars may be conveniently formed of heavy railroad iron and the lower ends are curved inwardly toward the wall and terminate a short distance from the lower wall of the chute so as to leave a restricted portion of the chute under the sole control of the gate member. The weight of the irons 21 is sufficient to enable them to normally retard the flow through the chute except as to the lower restricted portion which is under control of the gate member. A plurality of chains 23 are connected to the irons 21 and to the weight 17, and when the weight is in the lowermost position the chains hang loosely with some slack. After the weight has been elevated through approximately half its travel the slack in the chains will be taken up, and further upward movement of the weight will cause a lifting of the irons 21 by the chains 23. As the irons are lifted their restraining effect upon the pile of limestone or coal will be removed and a larger mass of the limestone or coal will pass through the chute. The connections between the cable and the gate member are such that during the first half of the upward movement of the weight, the gate member will be moved

to carry its upper restraining edge below the bottom wall of the chute, and the gate member will continue to move below the chute during the remaining upward movement of the weight while the finger bars or irons 21 are swung outwardly and upwardly to release the limestone or coal. A suitable elevating conveyor bucket 24 is mounted on a trackway 25 so that the bucket can be disposed below the chute and adjacent thereto for receiving the limestone or coal passing through the chute and can then be operated to carry the bucket upwardly to a point at which its contents may be discharged.

In the use of the device the bucket 24 is lowered below the chute and an attendant operates the controlling valve 19 of the air hoist by means of the cable 20. The energization of the air hoist causes an upward movement of the movable plunger 15 which carries the weight 17 upwardly against the action of gravity. As the weight 17 moves upwardly it will cause a movement of the cables 12 which will carry the gate member downwardly below the bottom wall of the chute and release the limestone or coal that is resting against the lateral wall 1 and against the gate member for movement into the bucket 24. When a sufficient quantity has been admitted to the bucket 24 the operator by another movement of the cable 20 will operate the air hoist to permit of a descent of the weight 17, and the latter in descending will carry the gate member upwardly to check the movement of coal or limestone from the chute into the bucket. The bucket may then be pulled upwardly to a point at which it may be discharged in a suitable manner, such as into a lime kiln. The control of the movements of the weight 17 by the valve member 19 of the air hoist is sufficient to insure a very accurate and reliable control of the gate member.

It frequently happens that the coal or limestone resting against the finger bars becomes packed together sufficiently so that when the gate member is dropped no movement of the coal or limestone will occur. In such situations it is necessary that some means be provided for starting the movement. In this device, after the gate member has been dropped below the lower wall of the chute, a further upward movement of the weight 17 will elevate finger bars 21 and release the mass of coal or limestone restrained thereby. Upon the starting of this movement, the finger bars may be lowered again by a lowering of the weight 17, so as to restrain the movement to a rate which may be readily controlled by the gate member.

We have found that this gate device is effective, economical and satisfactory in handling limestone and coal, but obviously it is equally applicable to the handling of

other substances having similar physical characteristics. It will be obvious that various changes in the details and arrangement of parts in the embodiment herein described for the purpose of explaining the nature of the invention may be made by those skilled in the art within the principle and scope of the invention.

Claims:

10. 1. In a gate device, a lateral wall having an aperture therein, a chute leading from the aperture, a gate member hinged for movement from a position below the chute upwardly across the lower part of the chute to variable extents, pulleys arranged above and below the chute, and an endless cable passing between and co-operating with said pulleys, said cable being connected at one point to said gate member to operate the latter in a direction dependent upon the direction of movement of the cable.
15. 2. In a gate device, a lateral wall having an aperture therein, a chute leading from the aperture, a gate member hinged for movement from a position below the chute upwardly across the lower part of the chute to variable extents, pulleys arranged above and below the chute, an endless cable passing between and co-operating with said pulleys, said cable being connected at one point to said gate member to operate the latter in a direction dependent upon the direction of movement of the cable, and a weight connected to said cable and adapted 20 when released to operate the same in one direction and thereby operate the gate member in one direction.
25. 3. In a gate device, a lateral wall having an aperture therein, a chute leading from the aperture, a gate member hinged for movement from a position below the chute upwardly across the lower part of the chute to variable extents, pulleys arranged above and below the chute, an endless cable passing between and co-operating with said pulleys, said cable being connected at one point to said gate member to operate the latter in a direction dependent upon the direction of movement of the cable, a weight connected to said cable and adapted 30 when released to operate the same in one direction and thereby operate the gate member in one direction, and a power device connected to operate the weight against the action of gravity.
35. 4. In a gate device, a lateral wall having an aperture, a chute leading from the aperture and having an inclined bottom wall, a gate member pivoted for movement upwardly or downwardly across the lower end of the chute to variably restrict the passage of material along said chute, pulleys arranged above and below the chute, an endless cable passing between and co-operating with said pulleys, said cable being connected at one 40 point to said gate member to operate the same in a direction dependent upon the direction of movement of the cable, and mechanical devices for operating the cable in both directions to cause corresponding movements of the gate member.
45. 5. In a gate device, a lateral wall having a discharge aperture, a gate member operable across the lower part of the aperture to various extents to check the passage of material through the aperture, a plurality of heavy finger bars freely suspended endwise across the upper part of said aperture for in and out movement and normally restricting movement of material through the aperture to the lower portion thereof which is under the sole control of the gate member, and means for swinging the bars outwardly and upwardly to start movement of the material through the aperture when the opening of the gate member fails to start it.
50. 6. In a gate device, a lateral wall having a discharge aperture, a gate member carried by the wall and operable across the lower part of the aperture to various extents to check the passage of material through the aperture, a weight, means including a connection between the weight and the gate member for operating the gate member in one direction when the weight falls by gravity, a power device for lifting the weight to cause an opposite movement of the gate member, heavy bars suspended endwise across the upper portion of said aperture and terminating above the lower wall of the aperture, connections between said bars and said weight whereby movement of the weight beyond a determined extent in opening the gate member will cause an outward movement of the bars to release the mass held in check by said bars.
55. 7. In a gate device, a lateral wall having a discharge aperture, a gate member carried by the wall and operable upwardly across the lower part of the aperture to various extents to check the passage of material through the aperture, a weight, a pulley above the aperture, a pulley below the aperture, an endless cable passing between and in operative relation with said pulleys and connected to said weight and to said gate member whereby the weight in falling will operate the gate member in one direction, a power device for lifting the weight to cause an operation of the gate member in the opposite direction, heavy bars suspended endwise in said aperture from a point adjacent the upper wall of the aperture and terminating some distance above the lower wall of the aperture, connections between the bars and said weight whereby movement of the weight beyond a determined extent in opening the gate member will cause an outward movement of the bars to release the mass held in check by said bars.

8. In a gate device, a lateral wall having a discharge aperture, an undercut gate member and overhung freely suspended weights for jointly controlling the passage of material through the aperture, and means partially common to the member and overhung weights for controlling their movements.

9. In a gate device, a lateral wall having a discharge aperture, an undercut gate member and overhung freely suspended weights for jointly controlling passage of material through the aperture, and mechanical mechanism for operating said member and weights to control the passage of material through the aperture.

10. In a gate device, a lateral wall having a discharge aperture, a gate member controlling the movement of material through the lower part of the aperture, relatively heavy bars freely suspended in the upper part of the aperture to control the movement of material through the upper part of the aperture and operable outwardly to permit outward movement of the material through the aperture, and mechanism operable to first open the gate member and then move the suspended bars outwardly.

11. In a gate device, a lateral wall having a discharge aperture, a gate member

controlling the passage of material through the lower portion of the aperture, and heavy bars suspended freely across the upper part of the aperture so as to control the movement of material through the upper part of the aperture.

12. In a gate device, a lateral wall having a discharge aperture, a gate member operable across the lower part of the aperture to various extents to check the passage of material through the aperture, a plurality of heavy finger bars freely suspended endwise across the upper part of said aperture for in and out movement and normally restricting movement of material through the aperture to the lower portion thereof which is under the sole control of the gate member, means for operating the gate, and a connection between the means and the bars whereby movement of the gate in an opening direction beyond a determined extent will cause an outward movement of the bars to release the mass normally held in check by the bars.

In witness whereof we hereunto subscribe our signatures.

GEORGE B. WOOD.
WILLIAM C. BIRD.
ERNEST B. PACKARD.
